UNITED STATES PATENT OFFICE.

AUGUST MORGANFIELD, OF JUNCTION CITY, KANSAS.

COLLAR-RECREASER.

1,156,307.

Specification of Letters Patent. Patented Oct. 12, 1915.

Application filed July 19, 1915. Serial No. 40,552.

To all whom it may concern:

Be it known that I, AUGUST MORGANFIELD, a citizen of the United States, residing in the city of Junction City, in the county of 5 Geary and State of Kansas, have invented certain new and useful Improvements in Collar-Recreasers, of which the following is a specification.

My invention is a collar recreasing device 10 believed to be a new article of manufacture and the object is to provide an implement which, though simple in construction, is effective in so reshaping the fold of what is known as a "turn-down collar" that the 15 necktie when placed within such collar may be readily pulled either way around the neck to bring the exposed ends to the desired relative length. I attain this object by means 20 of the construction hereinafter described and illustrated in the accompanying drawing, in which:—

Figure 1 is a perspective view of one form 25 of my invention in position to reform the fold; Fig. 2, a perspective view of one form of my device, and Fig. 3, a like view of another form thereof.

Like numerals of reference indicate similar parts in Figs. 1 and 2 which represent the same form of the device, while Fig. 3 in 30 so far as it differs in form from that of Fig. 2 will be separately described. The principle, however, is the same in both and still other forms of construction are possible without varying from the principle embodied in my invention.

I preferably make my device of metal 35 though it could be constructed of any other suitable material without departing from the principle involved.

Referring to Figs. 1 and 2. A single piece 40 of sheet metal, preferably about one inch wide and five inches long, its exact width and length being immaterial, is folded lengthwise in the middle, a narrow slit 4 is made lengthwise of the flat surface from 45 one end to a little more than the width of the deepest collars in vogue. Lips 1 and 2 are shaped from the two separable pieces thus formed by curving them from their 50 bases outward and upward as at 5, the space therebetween being approximately that of the full thickness of the ordinary collar. One such lip is sufficiently longer than the other to admit of its being horizontally

turned inward at its free end, thus forming 55 the projection or shoulder 3. The tongue strip 7, which is pressed together into practically one piece, is shortened so as to fit up in under the fold of the collar 8 when the lips 1 and 2 embrace opposite sides of the 60 collar and the shoulder 3 is lapped over the top of such fold. The lower portion 6 of the device is used as a handle.

Referring to Fig. 3. A single strip of sheet metal, preferably about one half inch 65 wide and sixteen inches long, the exact width and length, as before, being immaterial, is doubled crosswise nearly midway of its length, forming the tongue 14, the two portions 12 and 13, of which, for the purpose of 70 symmetry or lightness, may be somewhat reduced in width. The two lips 9 and 10 are curved outward and upward to parallel each other and inclose therebetween the tongue 14, the looped ends 11 forming springs. 75 The longer side 10 is turned inward, as in the other form of construction forming the projection or shoulder 3.

To use my device the tongue is inserted 80 from the under side between the folds of the collar with one lip on each side of such collar and shoulder 3 resting on the top of the fold of the collar. Then, by passing the device in that position along the length of the collar the fold is reformed and enlarged so that 85 when the collar with the tie therein is placed around the neck in the usual manner, the tie may be easily slipped backward and forward around the neck as desired, thus overcoming the great annoyance heretofore frequently 90 experienced in the adjustment of the tie because of the collar pinching it.

It will readily be seen that a device of this character without the shorter lip would still accomplish the purpose for which my invention is designed, but the construction shown and described is considered preferable.

What I claim is:—

An article of manufacture of the class described comprising a tongue adapted to be 100 placed within the fold of a collar, and an elongated lip provided with a shoulder projection adapted to overlap such fold.

AUGUST MORGANFIELD.
